M. W. BATTLE

MENU CARD HOLDER

Filed June 19. 1923

Inventor

Mary W. Battle.

334 *A. J. O'Brien*

Attorney

UNITED STATES PATENT OFFICE.

MARY W. BATTLE, OF DENVER, COLORADO.

MENU-CARD HOLDER.

Application filed June 19, 1923. Serial No. 646,368.

To all whom it may concern:

Be it known that I, MARY W. BATTLE, a citizen of the United States, residing at Denver, the city and county of Denver, and State of Colorado, have invented certain new and useful Improvements in Menu-Card Holders; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to menu card holders and has reference to an improved means for holding the card in place.

In menu card holders of this type, it is necessary to provide means whereby the card 20 can be readily removed, and whereby the same can be secured in place with a minimum amount of work.

It is customary in this type of holders to provide the holder with a pair of spaced 25 hooks which are adapted to project through the crease in the card and to connect the ends of the hooks by means of a rubber band. This construction, although it is practicable, is not as desirable as it should be and it is 30 my object to improve thereon.

In my present invention, I secure to the hinge pin a pair of spaced hooks which have a shank portion projecting through the menu card. Instead of connecting the hooks with 35 an elastic band, I provide a wire which has an opening near each end and which carries clamps that are adapted to engage the shanks and hold the wire in place.

In order to better and more clearly describe my invention, I shall have reference 40 to the accompanying drawing, in which:

Fig. 1 is a perspective view of a menu card holder in partly open position, showing the menu card held in place by my improved 45 means.

Fig. 2 is a view showing the hinge portion of the holder detached therefrom.

Fig. 3 is a section of the hinge portion taken on line 3—3, Fig. 2.

50 Fig. 4 is a side elevation of the card retaining wire.

Fig. 5 is a section of a portion of Fig. 1 taken on a line corresponding to line 3—3, Fig. 2, showing the construction of the 55 clamping member and the manner in which it is applied to the projecting member.

Fig. 6 is a section of the hinge and the clamping means, taken on line 6—6, Fig. 3.

The same reference numerals will be employed to designate the same parts throughout the several views.

Numeral 1 designates my menu card holder as a whole and 2 and 3 represent the cover sections which are hingedly connected. In Fig. 2 I have shown a perspective view 65 of the hinge which consists of two substantially identical hinge members 4 and 5 which are doubled over and have their creased side notched to form inter-engaging members 6 and 7 through which the hinge pin 8 passes. 70 Secured to the hinge pin 8 are two projecting members 9 and 10 which are preferably formed from a piece of wire which is doubled on itself to form the pins 9 and 10. One end 11 of the wire is bent into the 75 shape of an eyelet which embraces the hinge pin 18. The other end 13 of these wires is bent at right angles to the projections or shanks 9 and 10 and has at its extreme end an eyelet 14 which is adapted to receive a 80 pin 15 whose inner end projects into the opening in the hinge and which is held therein by means of solder 16. It is apparent that the projecting members 9 and 10 are free to rotate, to a limited extent, about 85 the axis of the hinge pin 12 and that by engaging the part 13 with the finger, the projecting parts 9 and 10 may be held so as to point in any desired direction whereby they can be readily inserted into openings 90 in the crease of the menu card 17. In order to hold the menu card in place, I provide a rod 18 which has at each end an eyelet 19. These eyelets are spaced apart the same distance as the projecting portions 9 and 10 95 in order that they may receive the projection. For the purpose of holding the rod 18 in place, I provide clamping members 20 which may be soldered to the ends of the wire or otherwise connected thereto. Each 100 clamp 20 consists of a casing 21, the opening through which is tapered as indicated by numeral 22. Within the casing there is reciprocably mounted a tubular member 23 whose inner end is split and provided with 105 cam members 24. A spring 25 surrounds the tubular member and abuts its ends against the cams 24 and the inwardly turned flange 26 on the end of the casing. The members 9 and 10 project into the opening 110 in the tubular members 22 and the rod 18 is held against withdrawal by the clamp-

ing action of the cams 24 in a manner readily apparent from an inspection of Fig. 5. The tubular members 23 have heads 27 which may be grasped whenever it is desired to release the rod 18.

I have shown the rod 18 as provided with eyelets or openings near each end, but it is evident that the rod may have its ends extending beyond the openings. If, for any reason, it might be found desirable to do so, the parts 13 and 14 may be omitted.

From the foregoing, it will be seen that I have provided a simple and effective means for securing a menu card in place in a holder. My retaining means is positive in its action, of neat and substantial construction and can be readily applied and removed.

Having now described my invention, what I claim as new is:

- 20 1. A menu card holder comprising a two-part cover hingedly connected, a pair of shanks secured to said holder near the hinge thereof, a rod provided with two spaced openings adapted to cooperate with said shanks, and means comprising a pair of clamping members for removably securing the rod in place, the clamping means being constructed to encase and conceal the said shanks.
- 25 2. A menu card holder comprising two cover members, each provided with interengaging hinge portions, a hinge pin co-

operating with said hinge portions, a pair of projecting members secured to said hinge pin at spaced points, a rod having openings spaced apart a distance equal to the distance of the projecting members whereby the latter may enter the holes, and spring operated clamping means cooperatively related to the rod and the projecting members for holding them in operative relation, the clamping means being constructed to encase and conceal the projecting member.

3. A menu card holder comprising in combination two cover members each provided with a plurality of complementary inter-engaging hinge portions, a hinge pin cooperating with said hinge portions for the purpose of hingedly connecting the cover members, and a member movably connected with the hinge pin, projecting outwardly therefrom and having a portion extending parallel therewith to facilitate manipulation.

4. A menu card holder comprising a two-part cover hingedly connected, a pair of shanks secured to said holder near the hinge thereof, a rod provided with spaced openings adapted to cooperate with said shanks and means comprising a pair of securing members for securing the rod to said shanks, the securing means being constructed to encase and conceal the said shanks.

In testimony whereof I affix my signature.
MARY W. BATTLE.
